UNITED STATES PATENT OFFICE.

UTLEY WEDGE, OF ARDMORE, PENNSYLVANIA.

METALLURGICAL FURNACE.

1,094,954.

Specification of Letters Patent. Patented Apr. 28, 1914.
Application filed July 16, 1913. Serial No. 779,261.

To all whom it may concern:

Be it known that I, UTLEY WEDGE, a citizen of the United States, residing in Ardmore, Pennsylvania, have invented certain 5 Improvements in Metallurgical Furnaces, of which the following is a specification.

The object of my invention is to construct a furnace, particularly one of the circular hearth type, in such manner as to provide 10 for the convenient conduct therein of processes that cannot be so conducted in furnaces of this type as ordinarily built.

This object I attain in the manner herein- 15 after set forth, reference being had to the accompanying drawing, in which—

Figure 1 represents in vertical section a furnace of the circular hearth type with superposed hearths constructed in accordance 20 with my invention, and Fig. 2 a furnace of the rotary horizontal type, embodying my invention.

The furnace shown in Fig. 1 may have any desired number of hearths, that shown in the drawing having seven hearths, numbered 25 consecutively from top to bottom, these hearths being supported upon the outer wall 8 and having central openings for the reception of the central rotating shaft 9 which is provided with projecting 30 rabble arms 10 intended to carry appropriate rabbles for stirring and feeding the material deposited upon the hearths. In the drawing, the rabbles are, for convenience, shown upon the arm which co-operates with 35 the hearth 2 only. Each of the hearths discharges through a suitable opening or openings onto the hearth beneath. Projecting upwardly from as many of the hearths as may be desired (from each of the hearths 40 except the uppermost in the present instance) is an annular rib 11, which divides the hearth into inner and outer zones 12 and 13, respectively. The rabbles upon the arms 10 are so disposed as to feed the material 45 over the zones 12 and 13 from the receiving to the discharge point. As shown in the drawings the direction of feed over the zones 12 is radial, the discharge openings being located alternately at the outer and at 50 the inner portions of said zones but the discharge openings of the zones 13 extend radially across the same and the material is fed by the rabbles in a circumferential course, the discharge opening of each zone being 55 slightly in advance of that of the zone beneath.

If an extended travel of the material is required each zone 13 may have but a single discharge opening in which case the material will be caused to travel throughout almost the entire circumference of the zone but if a lesser extent of travel in each zone is desired the number of discharge openings may be increased accordingly. The furnace is thus adapted for the performance of many operations which cannot be effectively performed in furnaces of the usual type, since in my improved furnace material of one character can traverse the inner zones of the hearths and material of another and different character can traverse the outer zones thereof, and the two operations can thus be conducted simultaneously, for instance, carbonaceous fuel may be burned upon the outer zones and a compound of sulfur and iron, such as a sulfid ore, may be caused to traverse the inner zones of the hearths, the combustion of the fuel in the outer zones producing over the inner zones a reducing atmosphere of such temperature 60 as to vaporize the sulfur and oxidize the iron in the material on the upper hearths or reduce the metallic oxid to the metallic state on the lower hearths, or, where a reducing atmosphere is not necessary the combustion 65 of the fuel on the outer zones may produce a heating gas for acting upon material on the inner zones, there being in neither case any admixture of material upon one zone with that upon the other zone. Where the 70 furnace is one of the muffle type the necessary heating of the hearths can be effected by products of combustion in the heating chambers of the hearths and the reducing atmosphere or other gaseous reagent can be produced and maintained by means of gases 75 evolved from suitable material deposited upon either the outer or the inner zone of a hearth.

In practice it is preferable to deposit the 80 carbonaceous fuel or other gas producing material upon the outer zone because in case of leakage of air through the walls of the furnace, such air will be compelled to mix with the evolved gases before it can gain access to the material on the inner zone, and in case a reducing atmosphere is to be maintained any air leaking into the furnace through the side walls would be deoxidized 85 before reaching the material on the inner zone.

Steam may be introduced as by a suitably

located pipe into those chambers of the furnace in which vaporization of sulfur and oxidation of metal is being effected for the purpose of supplying oxygen in such quantity and condition as to effect the desired oxidation of the metal without tending to promote the oxidation of the sulfur.

My invention is not necessarily limited to a vertical furnace and in Fig. 2 I have illustrated the application of the same to a furnace of the rotary horizontal type, the barrel of such furnace being provided with internal spiral ribs 11^a whereby it is separated into spiral hearths which are prevented from communicating with one another by means of said ribs, and either furnace may be constructed so as to provide more than two portions or zones on each hearth, if desired.

20 In order to prevent, in a furnace of the type shown in Fig. 2, feed of material to any other zone of the furnace than that which is intended to receive the same it is advisable to provide the feed spouts 14 with 25 valves which may be opened when the proper zone is beneath the spout and closed at other times. In Fig. 2 I have shown such valves in the form of slides 15 which can be reciprocated by a cam 16 on the driving shaft 30 17 of the furnace, said cam acting through a rod 18 upon a bell crank lever 19 which reciprocates the rod 20 to which the slides 15 are connected. Each of the spiral hearths of the furnace may also have an independent outlet so as to prevent the mixing of the discharge from one hearth with that from the other.

Where it is desired to prevent oxidation of the material on the inner zones of the hearths the discharge outlet therefrom may 40 be valved, as shown for instance at 21 and 22 in Fig. 1, so as to permit of the intermittent discharge of material without providing for any inflow of air.

45 I claim:

1. A cylindrical furnace having a hearth with means dividing the same into a plurality of zones, and means for moving material over each of said zones.

50 2. A furnace having a series of superposed hearths provided with structures for separating each hearth into independent portions, and means for moving material over each portion of the hearth and from hearth 55 to hearth of the series whereby such progressive movement can be effected without admixture of materials.

60 3. A cylindrical furnace having a series of superposed hearths provided with structures whereby each hearth is separated

into a plurality of zones, means for mechanically moving material over each of the zones and from hearth to hearth, the material on each zone being separated from that on the adjoining zone.

4. A cylindrical furnace having a hearth with a plurality of portions and a separating structure between them, means for feeding material independently to each portion of the hearth, and means for moving the material over each portion of the hearth.

5. A cylindrical furnace having a hearth with a plurality of portions and a separating structure between them, means for feeding material independently to each portion of the hearth, means for moving the material over the different portions of the hearth, and means for discharging the material from one portion of the hearth independently of the discharge from another portion 80 of the same.

6. A circular furnace having a hearth provided with means for separating said hearth into a plurality of zones, rabbles for moving the material over said zones, and a 85 rotating structure carrying said rabbles.

7. A circular furnace having a hearth with means for separating the same into a plurality of zones, a central rotating shaft having one or more rabble arms thereon, and 90 rabbles mounted in line respectively with the different zones of the hearth.

8. A circular furnace having a hearth with means for separating the same into a plurality of zones, a central rotating shaft, 95 one or more rabble arms thereon, rabbles co-operating with one zone and constructed to move the material over the same in one direction and rabbles co-operating with another zone and constructed to move the 100 material over the same in a different direction.

9. A circular furnace having a hearth with means for separating the same into a plurality of zones, rabbles for each zone, and 105 a rotating mechanism for said rabbles, the rabbles co-operating with one zone being constructed to move the material over the same in a circumferential course and those co-operating with another zone being constructed 110 to move the material over said zone in a radial course.

In testimony whereof, I have signed my name to this specification, in the presence of two subscribing witnesses.

UTLEY WEDGE.
